CLAIM

The ornamental design for a jacket, as shown and described.

DESCRIPTION

FIG. 1 is a front elevation view of a jacket according to the present invention;

FIG. 2 is a rear elevation view of the jacket of FIG. 1;

FIG. 3 is a side elevation view of the left side of the jacket of FIG. 1; and,

FIG. 4 is a side elevation view of the right side of the jacket of FIG. 1; and wherein in the drawing FIGS. 1-4 the dotted lines illustrate visible stitching patterns and are part of the claimed design.

1 Claim, 1 Drawing Sheet
